UNITED STATES PATENT OFFICE.

ALADAR KARASZ, OF NEW YORK, N. Y.

CORRUGATED ROOF.

Application filed May 15, 1924. Serial No. 713,432.

My invention relates to roof structures and has for its main object to provide a roof composed of sheets of corrugated paper pulp board, or other similar material, which will 5 be lighter in weight, cheaper in cost and easier in assembling than the roof structures used at present.

Another object of my invention is to provide securing means for said corrugated 10 pulp roofs which means will be easy to assemble or to dismantle, and which do not require nails or pegs, and do not cause any injury to the purlins of the roof or to the corrugated sheets themselves, thereby making 15 my roofs more resisting to weather influences than the roofs at present in use.

Other objects of this invention will be apparent as the specification of the same proceeds.

With the above and other objects in view, my invention mainly consists in providing 20 corrugated sheets of paper pulp board or other similar light and heat insulating materials or fabrics, making them water and fire proof, arranging them over longitudinally 25 set pairs of purlins on a usual roof construction, securing the lower sheets to said purlins by bolts or other similar removable means, said means carrying hook devices for 30 dropping the upper sheets into them, whereby the upper end of the lower sheets will not only be secured to the roof supporting structure, but itself, and all its securing means, will be permanently covered and protected 35 by the lower edges of the upper sheets.

For a full description of the invention and the merits thereof and also to acquire a knowledge of details of construction of the same for effecting the various results mentioned hereinbefore, reference is to be had 40 to the following description and accompanying drawings, forming part of this specification.

While the essential and characteristic features of the invention are susceptible of modification, still the preferred embodiment of the invention is illustrated in the accompanying drawings, in which:—

Fig. 1 is a fragmentary plan view of my 50 roof construction showing that portion of the same where the two corrugated sheets are joined and secured to one another by my improved clamp device,

Fig. 2 is a sectional view of the same, the 55 section being taken on the line 2—2 of Fig. 1, Fig. 3 is another sectional view, taken on

the line 3—3 of Fig. 1, and showing a cross section of a portion of my corrugated pulp board only,

Figs. 4 and 5, are plan and cross sectional 60 views, respectively, of an improved hook used in connection with my clamp device, while

Figs. 6 and 7 are fragmentary plan and sectional views of an improved plug board. 65

Referring more closely to the drawings, the numeral 8 designates the lower one of the two corrugated sheets, the joining and securing of which is shown by the drawing, while the upper one of said sheets is indicated by the character 9. At every place

where the covering sheets of my roof structure are joined in the length-wise direction I preferably provide two longitudinal purlins 70 10 and 11 closely set to one another but having a space 12 left between them and of suitable size to receive the screw bolt 13.

Only the lower one of the two roof covering sheets will be directly secured to said supports 10 and 11, while the upper one of the 80 corrugated sheets will be secured in its place in a manner to be described hereinafter. The lower corrugated sheet 8 reaches about as high as to cover both purlins 10 and 11, but does not rest directly on them since I preferably employ a right angular rest piece 14 underneath the same to bridge over the space between said two purlins, the rest piece being made of sheet metal and generally following the curve of the corrugated sheet. 85

The corrugated sheet 8 having been placed over said rest piece 14, the clamp device 15 is placed thereon having an elongated right angular shape and a curvature in the cross-wise direction following that of the corrugated sheet and ending in two fork-like extensions 16 bent doubly and upwardly to leave a space 17 between them and the body of the clamp device 15. Each of the three

elements just described, that is: the rest 100 piece 14, the lower corrugated sheet 8, and the hooked clamp 15, have elongated recesses designated respectively by the characters 18, 19 and 20, but into them, and after said three pieces have been suitably adjusted over 105 one another and over the purlins 10 and 11, the bolt 13 is passed through said recesses and through the space 12 and firmly secured in its position by the use of the washer 21 and nut 22 at the inner side of the roof 110 structure. The bolt 13 preferably has a square head 23 fitting into the slot 20 in the

clamp 15 so that it will be entirely flush with the outer surface of said clamp device when nut 22 firmly draws and secures it into its position. To support the head 23 and to prevent it from rotation while the nut 22 is being secured or loosened, the two sides of the slot 20 may have depending inclined extensions 24 and 25 pressed out of the material of the clamp 15 and integral therewith.

After having thus built up one layer of lower sheets 8, the upper sheets 9 will be secured to the same by simply dropping them into the spaces 17 of hooked clamps 15. The upper ends of the upper sheets 9 will then be secured to the next upper pair of purlins in the same manner as the upper ends of the lower corrugated sheets 8 have been secured to the purlins 10 and 11.

In case it is desired to renew the roofing entirely or any portion of the same, the nuts of the respective bolts 13 will be removed and all the elements of my securing clamps, as well as the respective sheets of roof covering, may then be entirely removed, irrespective of how long the roof has been in use and in what condition its elements are.

In Figs. 6 and 7, I show a novel form of corrugated sheet roofing material, the ridges 25' of which are not continuous but showing spaced apart breaks 26. At the breaks 26 the roofing sheet may be kept straight and at a depth corresponding to the lowest depths 35 of the valleys of corrugation. The breaks 26 may be arranged in a staggered or zig-zag manner in the adjacent ridges of corrugation. This novel roofing sheet is especially adapted to be used in connection with my hooked securing clamps and it not only 40 will give a novel and attractive appearance to my roof but it also will give additional strength to the roofing sheets and the flat portions 26 of the same will prevent the 45 side-way spreading of the roofing sheets caused by the flattening of the corrugations.

Instead of the nut 22, I may provide a slot through my bolt and a wedge therein whereby to secure said bolt or to release the 50 same.

As will be seen by inspecting the drawings, my roof construction will provide securing means which are stronger than nails, pegs and the like, heretofore mainly used 55 for securing the roofing materials, and which are easier to assemble or to dismantle than the means in use at present. The perforated part of every sheet is entirely cov-

ered by the unperforated part of the next upper sheet and so are all the elements of 60 the clamp so that water cannot get to them and they are protected against rust and other destructive effects of the atmosphere. The respective roofing sheets as well as the 65 elements of my securing device are provided with means to accommodate them to the valleys in the materials and to the possible variations in the structure, and in consequence the adjustments to be made are 70 easily done, resulting in efficient work and much saving in labor. Saving in lumber will also result since no boarding is needed and since the weight of the corrugated pulp is comparatively smaller than the roofing 75 materials used at present, and all the supporting structures may also be lighter than usual. The corrugated pulp board may be easily made water and fire proof, and since it is a heat insulator, less perils will result 80 in the case of a fire than when sheet metal or tile are used, while the attic will be cool in summer which makes my roof construction especially adaptable in the tropics or in climates with hot summers.

Having thus described my invention, what 85 I claim, is:

In a roof construction, a supporting structure having spaced apart pairs of longitudinal purlins, longitudinal rows of corrugated roofing sheets having longitudinally 90 over-lapping margins over said pairs of purlins, spaced apart elongated perforations in the lower ones of said over-lapping margins, a rest piece placed underneath each perforation having a curvature to fit the 95 curve of the valley of the roofing sheet corrugation and an elongated recess therein to meet the perforation in the roofing sheet, a clamp device having an elongated body portion to fit over the lower sheet at the 100 place of said perforation and showing a similar elongated perforation, a bolt passing through said three perforations and through the space between the two purlins, 105 said bolt having a head to rest in the perforation of said clamp device and removable securing means at its opposite end, the body of said clamp being continued in a downward extension doubled over itself to form a hook adapted to receive the lower margin 110 of the upper roofing sheet.

Signed at New York in the county of New York and State of New York, this 8th day of May A. D. 1924.

ALADAR KARASZ.
